UNITED STATES PATENT OFFICE

AUGUST F. PARIS, OF BROCKWAY, PENNSYLVANIA

WASHING-MACHINE CYLINDER

Application filed January 16, 1928. Serial No. 247,092.

The invention relates to improvements in cylinders for washing machines, primarily the so-called dry-cleaners, and it aims to provide a new and improved cylinder construction embodying separate uniquely formed compartments in which different apparel may be placed, for instance, articles of very delicate texture in one compartment, washable hats in another compartment and comparatively rough or coarse clothing and the like in a third compartment, permitting all of the articles to be washed at a single operation.

Another aim of the invention is to provide new and improved means for holding the hats in the compartment in which they are washed.

With the foregoing in view, the invention resides in the novel subject matter hereinafter described and claimed, description being accomplished by reference to the accompanying drawing.

Fig. 1 is a side elevation of the cylinder with the door of the hat washing compartment swung open.

Fig. 2 is a longitudinal sectional view on the plane indicated by line 2—2 of Fig. 4.

Fig. 3 is a vertical transverse sectional view on line 3—3 of Fig. 2, showing the doors partly opened.

Fig. 4 is a view similar to Fig. 3 but showing the doors closed and illustrating the manner in which hats may be held in the hat washing compartment.

Fig. 5 is a longitudinal sectional view on line 5—5 of Fig. 4.

The drawings above briefly described illustrate the preferred form of construction and while such construction will be herein specifically explained, it is to be understood that within the scope of the invention as claimed, variations may be made.

The numerals 6 denote two end members of circular outline and 7 has reference to a perforated cylindrical side wall which

extends between and is secured to said end members. This side wall 7 embodies two outwardly swingable doors 8—9 for auxiliary washing compartments hereinafter described, and a third door 10 for the main washing compartment, all doors being provided with suitable means for holding them in closed position.

Extending between the end members 6 and disposed between the axis of the cylinder and the doors 8—9 respectively, are two, perforated, auxiliary compartment bottoms 11—12, both of which are outwardly spaced from the aforesaid axis. Preferably, bottom 11 is concentric with the cylinder while bottom 12 is straight or flat. Perforated, auxiliary compartment side walls 13 extend from the longitudinal edges of the bottom 11 to the wall 7 and have their ends suitably secured to the end members 6, these side walls 13 being disposed at opposite sides of the opening which is normally closed by the door 8. Two additional, auxiliary compartment side walls 14, also perforated, extend between the longitudinal edges of the bottom 12 and the cylinder wall 7 and have their ends suitably secured to the end members 6, said side walls 14 being disposed at opposite sides of the opening which is normally closed by the door 9.

The parts so far described, provide a cylinder which embodies an auxiliary compartment 15 for articles of delicate texture, an auxiliary compartment 16 for hats, and a main compartment 17 for comparatively rough or coarse clothing, compartment 15 being provided with the door 8, compartment 16 with the door 9, and compartment 17 with the door 10. The articles to be washed may be placed in their respective compartments and held therein by fastening the doors closed, and then the contents of all compartments may be washed at a single operation, without danger of injury to any of them.

The ends of the compartments 16 are provided with grooves or other guideways 18 extending in directions from the door 9 toward the bottom 12, and in these grooves or guideways, the ends of perforated hat-holding boards 19, are removably received, said boards being disposed in parallel planes to straddle the crowns C of hats and to hold the hat brims B against the bottom 12. As long as the door 9 is closed, it abuts the outer edges of the boards 19 and hence holds the latter against removal. Upon opening of this door however, the boards 19 may be readily withdrawn from the grooves or guideways 18, permitting insertion or removal of the hats. After the hats are inserted, the boards 19 are of course replaced and the door 9 closed, so that said boards hold the hats securely in the washing compartment 16, to prevent possible injury during the washing operation and to insure more thorough cleaning than if they were not held in orderly fashion.

Excellent results are obtainable from the details disclosed and they are therefore preferably followed. However, within the scope of the invention as claimed, variations may be made, as above stated.

I claim:—

1. A washing machine cylinder comprising two end members, a cylindrical side wall extending between said end members and having a plurality of circumferentially spaced doors, elongated auxiliary compartments within said cylinder and each comprising a bottom extending between said end members and spaced outwardly from the cylinder axis, and two side walls extending from the longitudinal edges of said bottom to said cylindrical side wall; the bottoms of said auxiliary compartments being spaced apart circumferentially of the cylinder, the side walls of each of said auxiliary compartments being independent of the side walls of the adjacent auxiliary compartments; all of said doors but one opening into said auxiliary compartments, said one door opening into the portion of the cylinder unoccupied by said auxiliary compartments, which portion constitutes a main washing chamber in which the water will be agitated by the bottoms and side walls of said auxiliary compartments.

2. A washing machine cylinder provided with a compartment and a door opening into said compartment, opposed walls of said compartment being provided with guides each extending to the door opening, and an elongated member for holding articles against the compartment bottom, said member having its ends removably received in said guides, said door abutting said member when closed and holding it against removal.

3. A washing machine cylinder provided with a compartment for hats, means com-

prising movably mounted parallel members in said compartment to rest on the hat brims at opposite sides of the hat crowns to hold said brims against the compartment bottom, and means for normally holding said members in spaced relation with each other and in brim-clamping relation with said bottom.

In testimony whereof I have hereunto affixed my signature.

AUGUST F. PARIS.
